UNITED STATES PATENT OFFICE.

JAMES ALEXANDER FLANAGAN, OF TORONTO, ONTARIO, CANADA.

FEEDING MECHANISM FOR SEWING-MACHINES.

1,387,145.

Specification of Letters Patent.

Patented Aug. 9, 1921.

Application filed June 17, 1919, Serial No. 304,792. Renewed June 9, 1921. Serial No. 476,345.

To all whom it may concern:

Be it known that I, JAMES ALEXANDER FLANAGAN, a British subject, and resident of the city of Toronto, in the county of York 5 and Province of Ontario, Dominion of Canada, have invented certain new and useful Improvements in Feeding Mechanism for Sewing-Machines; and I hereby declare the following to be a full, clear, and exact description of the same.

My present invention relates to a specially designed feeding mechanism for sewing machines, this mechanism comprising a slide vertically reciprocated by the rotation of 15 the looper shaft and a feed dog reciprocating vertically with the slide and having lateral reciprocating movement independently of it, imparted by the rocking action of the feed shaft.

For an understanding of the invention, I have shown and described it in connection with the feed and looper motions forming the subject matter of my application for Letters Patent, Serial Number 274902, filed 20 February 4th, 1919, in which the feed and looper shafts are in coaxial relation, but the invention may, by alterations and changes within the scope of the claims, be adapted for other types of feed and looper motions.

In the accompanying drawings:

Figure 1, is a sectional elevational view of so much of a sewing machine as is necessary to illustrate the present invention.

Fig. 2, is a side sectional elevational view 35 of the feeding mechanism on a larger scale than Fig. 1,

Fig. 3, is an elevational view showing the vertical slideway for the feed slide,

Fig. 4, is a plan view of the slideway 40 shown in Fig. 3, and

Fig. 5, is an elevational view of the feed slide, the feed dog and the feed cam.

As an illustration of how the invention 45 may be carried into effect I have shown in Figs. 1 and 2, a tubular feed shaft *a* journaled in suitable bearings *b*, *b'*, forming part of, or rigidly connected to the frame *c*.

I have also shown in the same figures a 50 looper shaft *d*, extending axially through the feed shaft and projecting beyond the ends thereof, this arrangement bringing the feed and looper shafts into co-axial relation.

The feed shaft *a* is provided at or near 55 its front end with a radial arm *e* extending in the direction of the throat plate *c'*. This arm *e* is provided with a hub *e'* the rear face

of which is formed with a bore *e''* to receive the front end of the feed shaft *a*, the hub and shaft being pinned, keyed or otherwise fastened together for their united movement. The hub *e'* extends forwardly beyond the shaft *a* and is bored to receive, and serve as a bearing *e'''*, for the front end of the looper shaft *d*, and fixed on the rear end of the feed shaft is a cap bored to form the rear bearing *e''* for the looper shaft *d*.

Bolted or otherwise stationarily fastened to the front face of the bearing *b* is a block *h* having a recess *h'* of such shape and dimensions as will permit of the oscillating movement of the arm *e*. In the block *h* at the sides of the recess *h'* are slideways *h''*, and vertically movable in the slideways *h''* is the feed slide *i*. As shown in the drawings the top of the feed slide *i* is formed with a dovetail groove *j*, which serves as a slideway for the laterally reciprocating feed dog *l*, having a dovetail tongue *k*, which enters within the dovetail groove *j* and provides the sliding connection between these two parts. The dovetail formation of the groove *j* and tongue *k* may be varied or modified from that shown in the drawings as any other type of a sliding connection between these parts may be substituted for those shown and described. Projecting from the feed dog *l* is a pin *m*, which takes in an elongated slot *o* in the oscillating arm *e*, the elongation of the slot *o* being in a radial direction from the center of the feed shaft 80 and of sufficient length to provide for the full vertical movement of the feed dog during its rise and fall.

In the feed slide *i* is a bore *i'* and fixed on the looper shaft is a cam *p*, operating within the bore *i'* and causing the rise and fall of the feed slide during the revolution of the looper shaft and imparting to the feed slide a reciprocating movement.

The cam *p* is so timed and designed as to 100 come into engagement with the top of the bore *i'* and positively lift the feed slide *i* to its elevated position when the needle has delivered the thread to the hook and receded from the material. While the slide is in this position the feed dog is reciprocated forwardly by the action of the arm *e*. The cam *p* then positively lowers the feed slide to the limit of its downward reciprocation for the feed dog to release the work.

When the slide is at the limit of its downward reciprocation the arm *e* moves the feed

dog rearward to again engage the material when the slide is raised to the limit of its upward reciprocation. In this way a positive vertical reciprocation of the slide and feed dog is effected by means of the cam p , and a positive lateral reciprocation of the feed dog independently of the slide is effected by the arm e , the lateral reciprocation of the feed dog being in a plane parallel with the work.

From the foregoing it will be understood that during the revolution of the looper shaft the cam p alternately comes into contact with the top of the bore i' to raise the feed slide to the limit of its upward reciprocation, and momentarily maintain it stationary for the feed dog to move the work forwardly, and that when the work has been fed forward for the next stitch the cam p comes into contact with the bottom of the bore i' and causes the descent of the feed slide i to the limit of its downward reciprocation, during which the feed dog releases the work and moves rearwardly for the next stitch. The elongated slot o is of sufficient length to permit of the rise and fall of the pin m , to the full depth of the vertical movement of the feed dog and feed slide i . The feed shaft a is reciprocated by a suitable drive r preferably connected with the cap forming the rear bearing e^4 for the looper shaft, and a rotating motion is imparted to the looper shaft d by any suitable drive s connected with it, the looper shaft projecting beyond the rear bearing for that purpose.

By means of this construction a positive vertical reciprocation is imparted to the feed dog by the looper shaft, and a positive lateral reciprocation is imparted to it by the feed shaft.

Having thus fully described my invention, what I claim as new and desire to secure by Letters Patent, is:

45 1. A feeding mechanism for sewing machines comprising a reciprocating feed slide, having an open center, a hollow feed shaft, a looper shaft extending through the feed shaft, a cam on the looper shaft within the 50 open center of the slide, causing its reciprocation, a feed dog having a lateral sliding connection with the slide for reciprocation therewith, and means rocked by the feed shaft, causing the reciprocation of the feed dog laterally with respect to the slide during its reciprocation by the cam.

2. A feeding mechanism for sewing machines comprising a reciprocating feed slide, having an open center, a hollow feed shaft, a looper shaft extending through the feed 60 shaft, a cam on the looper shaft within the open center of the slide, causing its reciprocation, a feed dog having a lateral sliding connection with the slide for reciprocation therewith, and a rocker arm connected with 65 the feed shaft, causing the reciprocation of the feed dog laterally with respect to the slide during its reciprocation by the cam.

3. A feeding mechanism for sewing machines comprising a vertical slideway, a feed 70 slide having an open center movable in the slideway, a hollow feed shaft, a looper shaft extended through the feed shaft, a cam on the looper shaft operating in the open center of the slide and causing its reciprocation, a 75 feed dog having a lateral sliding connection with the slide for reciprocation therewith, and means rocked by the feed shaft causing the reciprocation of the feed dog laterally with respect to the slide during its reciprocation by the cam.

4. A feeding mechanism for sewing machines comprising feed and looper shafts, a vertically reciprocating slide having an aperture therein, a cam rotated by the looper 80 shaft operating in said aperture and causing the vertical reciprocation of said slide, a laterally reciprocating feed dog vertically reciprocating with said slide, an arm oscillated by the feed shaft having an elongated radial slot therein and a pin for said feed dog entering within said slot for the lateral reciprocation of the feed dog during the oscillation of the arm.

5. A feeding mechanism for sewing machines comprising feed and looper shafts, a vertically reciprocating slide having an aperture therein, a cam rotated by the looper 85 shaft operating in said aperture and causing the vertical reciprocation of said slide; a laterally reciprocating feed dog vertically reciprocating with said slide, an arm connected with the feed shaft and oscillated thereby, causing the lateral reciprocation of the feed dog, and a stationary slideway for 90 the vertically reciprocating slide.

Toronto, June 9th, 1919.

JAMES ALEXANDER FLANAGAN.
